2,192,935

ESTERS OF POLYCYCLIC ALCOHOLS AND A
METHOD OF PRODUCING THE SAMEWalter Schoeller, Berlin, Germany, assignor, by
mesne assignments, to Schering Corporation,
Bloomfield, N. J., a corporation of New JerseyNo Drawing. Application April 6, 1935, Serial
No. 15,100. In Germany April 7, 1934

17 Claims. (Cl. 260—397)

This invention relates to esters of polycyclic alcohols and more particularly to esters of the cyclopentano polyhydro phenanthrene series, having the characteristics of germinal gland hormones, and a method of producing the same.

In the copending application Serial No. 7,604, filed February 21, 1935, a process is described according to which esters of polycyclic alcohols with germinal gland hormone characteristics are obtained by subjecting acyl derivatives of the following structural formula:

wherein X represents either hydrogen or an alkyl or aryl group, Y either hydrogen or a hydroxy group, and R an acyl group, to the action of reducing agents capable of hydrogenating the benzene nucleus in the molecule of said starting material into a hydroaromatic nucleus, so as to form compounds of the structural formula:

The starting materials used for carrying out said hydrogenation process are, for instance, mono-acylated follicle hormone hydrate or mono-acylated dihydro follicle hormone and the like, i. e., compounds having the characteristics of the female sex hormones, whilst the reaction products obtained by the hydrogenation possess the characteristics of the male sex hormones.

Now, it has been found that one can arrive at esters of polycyclic alcohols of similar constitution, having also the characteristics of the male sex hormones, by reducing in the same manner the esters of the male sex hormones $C_{19}H_{30}O_2$ and $C_{19}H_{28}O_2$ and the like compounds as they are obtained, for instance, by the processes of the copending U. S. application Serial No. 723,928, filed May 4, 1934 (which describes a method for the purification of hormones by acylation, separation of the ester, and subsequent saponifi-

cation), the German Patents Nos. 576,967 and 583,854 from natural sources, such as urine and the like, or synthetically, for instance, by oxidation of the sterols, such as cholesterol and the like, in which latter case crystalline products will necessarily be obtained. Thus, when synthetically produced esters of androsterone, its isomer, or dehydro-androsterone are employed, as in Examples 3, 4, 5, and 6, crystalline hydrogenation products will always be obtained.

Not only the pure acyl compounds may be subjected to this reducing treatment, but also more or less impure preparations which then are purified, if required, after reduction has taken place.

Said starting materials correspond to the following structural formulas:

 $C_{19}H_{29}(OR)O$ $C_{19}H_{27}(OR)O$ wherein R represents an acyl group.

The reduction products obtained thereby have the following structural formula:

 $C_{19}H_{29}(OR)OH$ wherein R represents an acyl group.

Hence, by the present invention the keto group present in the cyclopentano ring is transformed into a secondary alcohol group yielding substances of a very high physiological activity.

The reduction is carried out according to reduction methods as they are known for transforming keto group into secondary alcohol groups. For this purpose the starting materials are subjected to the action either of catalytically activated hydrogen or of hydrogen in statu nascendi or of atomic hydrogen. The reduction is preferably carried out in solution of a suitable solvent. Care must be taken, however, that only

55

the keto group is reduced to the secondary alcohol group without complete reduction to the desoxo product taking place. In the case of the esters of the dehydro androsterone $C_{19}H_{28}O_2$, the double bond in ring 2 of the molecule is saturated during the reduction process so that products of the same general formula $C_{19}H_{30}(OR)OH$ are obtained from the saturated as well as from the unsaturated starting materials.

10 Of course, instead of using the acylated compounds as starting materials, one may proceed in such a manner that the non-acylated compounds are subjected to said reducing treatment under conditions whereby acylation may take place 15 simultaneously.

Furthermore, the monacyl products obtained may be converted, if desired, into the corresponding diacyl compounds by further acylation of the secondary hydroxy group obtained by the reduction 20 of the keto group.

The reaction products obtained in accordance with the present invention are valuable substances which are either effective physiologically themselves or can be further treated to yield 25 physiologically valuable materials. Thus, for example, the mono and diacetates of androstandiol exhibit a physiological activity in the cock-comb test which is three to four times that of the monoacetate of androsterone; the same is true of the 30 monobenzoate of androstandiol as compared with the monobenzoate of androsterone.

The following examples serve to illustrate the invention, without, however, limiting the same to them.

Example 1

1 g. of 3-acetyl androsterone, obtained according to Example 3 of the German Patent 576,967, is dissolved in 200 cc. of ethanol and, after the 40 addition of the same amount of a previously reduced nickel catalyst, is treated at 170° and 80-100 atmospheres pressure with hydrogen in an autoclave provided with a stirring device. After about 1 molecule of hydrogen is absorbed, the 45 reaction solution is freed from the catalyst, whereupon it is evaporated to dryness. A viscous resin is obtained as residue.

Example 2

50 1 g. of the phthalic acid ester of the male germinal gland hormone produced according to Example 1 of the German Patent 583,854 is hydrogenated by shaking with hydrogen at room temperature in glacial acetic acid solution in the presence of a platinum oxide catalyst made according to Adams-Shriner. The reaction mixture is freed from the catalyst and is then evaporated to dryness in a vacuum. By this means 55 the corresponding monoester of androstandiol is obtained.

Example 3

1 g. of the monobenzoic acid ester of androsterone are dissolved in 25 cc. of glacial acetic acid and are treated at room-temperature with 65 hydrogen in the presence of 0.5 g. of previously reduced platinum oxide catalyst while shaking or stirring. After absorption of about 1 molecule of hydrogen the hydrogen supply is interrupted, the catalyst is filtered off, the filtrate is poured in water, extracted with ether, the ethereal solution is washed free from acid by means of diluted alkali lye and water and the ether is distilled off after drying. A mixture of isomeric monobenzoic acid esters of the androstandiol remains, which 70 is recrystallized from dilute alcohol.

Example 4

1 g. of the monopropionate of the dehydro androsterone is reduced in the same manner as described in Example 3 with hydrogen in the presence of a platinum oxide catalyst, whereby 5 anhydrous propionic acid is used as solvent. After absorption of 2 molecules of hydrogen, on working up according to Example 3 a mixture of isomeric monopropionates of androstandiol is obtained.

Example 5

1 g. of the monobenzoate of dehydro androsterone is mixed with 250 g. of methyl cyclohexane and is reduced in an autoclave provided 15 with a stirring device at 90-100° C. and a pressure of 20 atmospheres with hydrogen in the presence of 8 g. of a highly active nickel catalyst as it is obtained, for instance, according to Raney, Journ. Am. Chem. Soc., vol. 54, page 4116 (1932). 20 As soon as the hydrogen absorption ceases, the solution is cooled and freed from the catalyst by filtration, whereupon the solvent is evaporated in a vacuum. The residue is recrystallized from dilute alcohol and represents the monobenzoate 25 of an androstandiol.

Example 6

1 g. of the acetate of hydroxy etio allo cholanone (17), i. e., an isomer of androsterone, is 30 dissolved in 50 cc. of 96% alcohol and heated to 60° C. While stirring vigorously an amount of freshly prepared 3% sodium amalgam in excess is added thereto in the course of 1 hour. By adding drop by drop small amounts of acetic acid 35 to this reaction mixture care is taken that the solution is always kept somewhat acid. When the amalgam is added the reaction mixture is heated for a further half hour at 60° C., poured in water and extracted with ether. After shaking with dilute alkali lye the ethereal extract is evaporated to dryness whereby the monoacetate of a 3,17-dihydroxy etio allo cholane is obtained.

Example 7

45 1 g. of androsterone is dissolved in 30 cc. of glacial acetic acid and is treated with hydrogen at about 80° C. in the presence of 0.5 g. of a previously reduced platinum oxide catalyst and of 3 cc. of a 48% aqueous hydrobromic acid. After 50 absorption of 1 molecule of hydrogen 10 cc. of acetic acid anhydride are added and the reaction mixture is allowed to stand over night in order to complete the acetylation. Thereupon it is poured in water and worked up as described in 55 the preceding examples. The diacetate of androstandiol is obtained.

In the same manner there may be obtained from the corresponding monacyl androsterones in one operation the corresponding diacyl compounds. One may also proceed in such a manner that the diketones obtained by the oxidation of the androsterones, i. e. androstandion and androstendion, are reduced and then acylated to 60 the corresponding diacyl compounds.

Example 8

70 2 g. of androsterone acetate are dissolved in 40 cc. of glacial acetic acid and are reduced with hydrogen at room-temperature in the presence of 1 g. of a platinum oxide catalyst according to Adam-Shriner (see Journ. Am. Chem. Soc., volume 45, page 2171 (1923)). Thereupon the glacial acetic acid is distilled off in a high vacuum at a temperature as low as possible. The residue 75

is then treated with benzoyl chloride in the presence of pyridine whereby an isomeric mixture of the 3-acetyl-17-benzoyl-androstandiol is obtained.

5 In a similar manner, there may be transformed other esters of the androsterones, such as the stearate, the succinate, the salicylate, the lactate and the like, into the corresponding esters of the androstandiol, likewise the esters of the dehydro androsterone yield similar androstandiol esters.

10 Of course, many variations and changes may be made in the reaction conditions and the starting materials etc. by those skilled in the art in accordance with the principles set forth herein and in the claims annexed hereto.

15 What I claim is:

1. A method for the production of esters of polycyclic alcohols of the general formula $C_{19}H_{30}(OR)OR'$ and the structural formula:

30 wherein R represents an acyl group and R' represents either hydrogen or an acyl group, comprising subjecting esters of hydroxy ketones of the group consisting of the male sex hormones $C_{19}H_{30}O_2$ and $C_{19}H_{28}O_2$ and their stereo isomers, to the action of agents capable of transforming the keto group in said hydroxy ketones into the secondary alcohol group.

35 2. A method for the production of esters of polycyclic alcohols of the general formula $C_{19}H_{30}(OR)OR'$ and the structural formula:

45 wherein R represents an acyl group and R' represents either hydrogen or an acyl group, comprising subjecting esters of hydroxy ketones of the group consisting of the male sex hormones $C_{19}H_{30}O_2$ and $C_{19}H_{28}O_2$ and their stereo isomers, to the action of agents capable of transforming the keto group in said hydroxy ketones into the secondary alcohol group, and acylating said secondary alcohol group formed thereby.

50 3. A method for the production of esters of polycyclic alcohols of the general formula $C_{19}H_{30}(OR)OR'$ and the structural formula:

65 wherein R represents an acyl group and R' represents either hydrogen or an acyl group, comprising

subjecting esters of hydroxy ketones of the group consisting of the male sex hormones $C_{19}H_{30}O_2$ and $C_{19}H_{28}O_2$ and their stereo isomers, to the action of catalytically activated hydrogen in the presence of hydrogenation catalysts so as to transform the keto group in said hydroxy ketones into the secondary alcohol group.

70 4. A method for the production of esters of polycyclic alcohols of the general formula $C_{19}H_{30}(OR)OR'$ and the structural formula:

85 wherein R represents an acyl group and R' represents either hydrogen or an acyl group, comprising subjecting esters of hydroxy ketones of the group consisting of the male sex hormones $C_{19}H_{30}O_2$ and $C_{19}H_{28}O_2$ and their stereo isomers, to the action of hydrogen in statu nascendi, so as to transform the keto group in said hydroxy ketones into the secondary alcohol group.

90 5. A method for the production of esters of polycyclic alcohols of the general formula $C_{19}H_{30}(OR)OR'$ and the structural formula:

105 wherein R represents an acyl group and R' represents either hydrogen or an acyl group, comprising subjecting hydroxy ketones of the group consisting of the male sex hormones androsterones $C_{19}H_{30}O_2$ dehydro androsterone $C_{19}H_{28}O_2$ and their stereo isomers, to the action of catalytically activated hydrogen in the presence of hydrogenation catalysts and acylating agents so as to transform the keto group in said hydroxy ketones into the secondary alcohol group whereby 110 simultaneously acylation of the hydroxy groups takes place.

115 6. Esters of polycyclic alcohols of the general formula $C_{19}H_{30}(OR)OR'$ and the following structural formula:

130 wherein R represents an acyl group and R' a member of the group consisting of hydrogen and acyl groups.

7. The monoacetate of an androstandiol of the general formula $C_{19}H_{28}O_2$, said monoacetate corresponding to the following structural formula:

5

10

15

and having a physiological activity about 3 times as high as that of the corresponding monoacetate of the male sex hormone androsterone.

20

8. A method for the production of esters of polycyclic alcohols of the general formula $C_{19}H_{30}(OR)OR'$ and the structural formula:

25

30

35

wherein R represents an acyl group and R' either hydrogen or an acyl group, comprising subjecting diketones as they are obtained by the oxidation of the hydroxy ketones of the group consisting of the male sex hormones androsterone

40

$C_{19}H_{30}O_2$ and dehydro androsterone $C_{19}H_{28}O_2$ and their stereo isomers, to the action of a reducing agent capable of reducing the keto groups in said diketones into secondary alcohol groups, in the presence of acylating agents so as to form

45

the above mentioned diacyl esters of polycyclic alcohols.

9. The monoester of an androstandiol having the structural formula

50

55

60

where R is an acyl group.

10. The monoacetate of an androstandiol having the structural formula

65

70

75

11. A method for the production of esters of polycyclic alcohols having the formula

5

10

15

wherein R represents an acyl group, comprising subjecting the esters of hydroxy ketones of the formula

25

30

35

wherein R represents an acyl group, to the action of reducing agents capable of transforming the keto group into the secondary alcohol group.

12. The monoester of an androstandiol having the structural formula

45

50

55

wherein R is an aliphatic acyl group.

13. A method for the production of esters of polycyclic alcohols having the formula

60

65

70

wherein R represents an acyl group, comprising

subjecting an ester of a hydroxy ketone of the formula

5

10

wherein R represents an acyl group, in the presence of an acid to the action of reducing agents capable of transforming the keto group into the 15 secondary alcohol group.

14. The monoester of an androstandiol having the structural formula

20

25

wherein R represents a dicarboxylic organic acid group.

15. Esters of polycyclic alcohols of the general formula $C_{19}H_{30}(OR)OR'$ and the following structural formula

5

10

wherein R and R' represent different acyl groups. 15

16. A method for the production of 3-esters of polycyclic dialcohols comprising subjecting a 3-ester of a hydroxyketone of the group consisting of the male sex hormones $C_{19}H_{30}O_2$ and $C_{19}H_{28}O_2$ and their stereo isomers, to the action of an agent capable of transforming the keto group in said hydroxyketones into a secondary alcohol group.

17. A method for the production of 3-esters of polycyclic dialcohols comprising subjecting a 3-ester of dehydroandrosterone to the action of agents capable of transforming the keto group in said dehydroandrosterone into a secondary alcohol group.

WALTER SCHOELLER. 30
